Thomas Beatty & Michael Shanks, Citizens of the United States
Sellers Patent

Dated 25th February 1818.

Memorandum of the schedule referred to in these Sellers Patent, and
making part of the same, containing a description in the words of this said Thomas
Beatty and Michael Shanks themselves of their improvement in the Thrashing
Machine.

This machine consists of the outward frame and case; the outward base or
cylinders or rubbers with protuberant or diamond points; the rack to be wheeled through
grain full; and the riddle and fan for cleaning the grain.

To construct a machine for a two horse power, the frame will be about 11 feet
high, 12 feet long, and 5 feet wide. The inner cylinder will be about 3 feet and a half in
diameter, covered with cast iron slaves with protuberant or diamond points or rubbers
rubbing out the grain. The outward cylinder or case will be made to surround the former
and be set about three-fourths of an inch distant from it; and will also be covered in
the manner with said cast iron slaves with projecting points. The distance of these
cylinders from each other, may be varied according to the size of the grain intended to
be thrashed. The outward or concave cylinder will have two suitable openings, one at
the top to admit the grain to be thrashed; and the other at the side for discharging it
when thrashed. The fan is placed at the end of the machine for receiving the grain when
thrashed; and has a wire screen for its bottom.

Operation of the Machine.

The machine is fed at the top or side by a person standing in an opening made
for the purpose. The inner cylinder is turned by any convenient power for which purpose
there will be suitable gearing; each cylinder rubbing the grain against the outer
or concave one completely disengages it from the straw and hull. By the motion
of the inner cylinder the grain and straw are carried round till they are dischar-
ged at the opening in the side of the case for that purpose. The grain and straw
thus falling on the rack, the straw passes off and the grain falls through, where it is
conducted by a hopper to the riddle; it then passes down through the blast of the fan
where it is completely cleaned.

This machine is calculated to thresh or rub out all kinds of small grain, and for shelling rice, &c.

When used for getting out clover seed or rubbing wheat the cylinder may be made a conical shape, and will be placed at any convenient distance from each other by screws at their sides.

In front of the machine where [oblique aled . . . . . Imagine a wire screen which will admit the [. . . . . By the wind, but prevents the grain.
